STOKER

William Thompson Hanna, Cincinnati, Ohio

Original application June 18, 1928, Serial No. 286,222. Divided and this application June 13, 1936, Serial No. 85,165

3 Claims. (Cl. 110—101)

This invention relates to stokers for use on locomotives and steamboats, and more particularly to a conical type of worm for use in a stoker wherein fuel is conveyed to a housing joining with a fuel entrance of a firebox, the conical worm being mounted within the housing generally below and to the rear of a ledge over which the fuel flows out of the housing to the fuel entrance. This case is a division of my copending application Serial No. 286,222, filed June 18, 1928, issued June 16, 1936, Patent Number 2,044,001.

One of the objects of the invention is to provide an improved type of conical worm for use in a stoker wherein conical worms are provided generally below and to the rear of a ledge of a conduit joining with a fuel entrance of a firebox. This and other apparent objects and advantages are obtained by the means described in the following specification and disclosed in the accompanying drawings wherein—

Figure 1 shows a vertical sectional view of a stoker mechanism embodying this invention, taken substantially on a longitudinal center line;

Figure 2 is a vertical transverse section of the same, taken substantially on a line 2—2 of Figure 1;

Figure 3 is a horizontal section of the same, taken substantially on a line 3—3 of Figure 1;

Figure 4 is a side elevation partially in vertical longitudinal section, showing a stoker of this character coacting with a locomotive and a tender;

Figure 5 is a top plan view of the interior of the housing of Figure 1; and

Figure 6 is a vertical section taken on line 6—6 of Figure 3.

In the drawings, as shown in Figures 1 to 4, numeral 1 represents the backhead of a locomotive firebox having a conventional firing opening 2 within which is located fuel distributing mechanism, generally indicated at 18, for distributing fuel over the fire bed. Embracing this opening, and rigidly mounted on the backhead, is a fuel or fire door housing 3. Connected to the base 45 of the housing, and forming a downwardly rearwardly projecting extension, is a conduit 4 through which fuel moves upwardly into housing 3. The extension 4 increases in cross-sectional area from its lower to upper extremities, so that 50 fuel moving up through it is constantly relieved of pressure at its sides (see Figure 3) and tendency of the fuel to clog while passing therethrough is offset. Extending rearwardly from conduit 4 (Figure 4) is conduit 6, which in turn 55 is connected to the front end of a hopper 8 be-

neath a tender 9. Suitable conveyors 7 in hopper 8, and 5 in conduit 6, serve to move the fuel forwardly into the housing 3.

The connections between hopper 8 and conduit 6, and between conduit 6 and extension 4, are of the ball and socket type. The conduit 6, in addition, has a sliding joint in the extension 4. These joints provide a substantially universal joint connection between the conduit 6, hopper 8 and extension 4 whereby changes in the relative positions, or a displacement of the tender from the locomotive, are accommodated.

As shown in Figure 4, conveyor 7 is driven by a gear 10 which is driven by a shaft 11 suitably mounted for rotation on the frame of the trough 8 and carrying a gear (not shown) which engages the gear 10. The shaft 11 has operative engagement with a steam motor, or other source of motive power, 12, through suitable connection as, for example, the telescopic shaft 13.

The housing 3 (Figure 5) is provided with recesses generally indicated at 111 and 112, respectively, formed in either side of the wall of the housing adjacent the backhead 1. The recesses have conically shaped concave fuel-supporting surfaces 113 and 114, respectively, which surfaces intersect the forward wall 3e of the housing to form edges or ledges 115 and 116, respectively, over which fuel rising from the extension 4 flows into the recesses 111 and 112.

The housing is provided at either side with cap plates 16 and 17 in which are suitably journaled conical worms, or fuel-conditioning or manipulating devices, 14 and 15 suitably driven by gearing (not shown) mounted in the housings 51 and 35 operated by gear levers 57 extending through openings 51a provided in the housings. The gearing is driven by motor 12 through suitable drive shafts 60. Each conical worm extends transversely of the housing or conduit and is recessed 40 in its respective recess out of the direct path of the fuel. These worms improve the stoking efficiency of the stoker by insuring the flow of the fuel flowing to the distributing means in a regulated stream. They act upon the column of fuel 45 rising in the housing to spread the fuel and transform it into form relatively thinner than the bulk of fuel in the conduit 4, and so regulate the presentation of the fuel to the firebox. In thinning the fuel in this manner its form is changed 50 as to thickness, density, consistency, and so forth, and the fuel reaches the distributing mechanism in a manner conductive to efficient distribution over the fire. The worms effectively shave or take fuel from the underside of the column and 55

present it to the ledge 3a of the housing over which it flows to the distributing mechanism generally indicated at 18 and fully described in the above-mentioned patent.

5 Fuel guides 37 and 38 are also provided to regulate the effective length of the ledge 3a. The slides are manipulated by suitable handles 39 and 40, respectively, mounted at pivot points 41 and 42 on arms 3b extending from the housing.

10 In firing a locomotive firebox it is desirable to supply more fuel to the extreme sides of the firebed than to the central area thereof in order to maintain a uniform draft up through the firebed. To this end it is desirable to increase the fuel-handling capacity of the worms 14 and 15 over and above that which naturally attends their conical construction. In the present embodiment this is accomplished by providing additional vanes 14a and 15a on the worms 14 and 20 15, respectively, the auxiliary vanes being located at the enlarged (mounted) ends of the worms, but not extending to the free ends thereof. With this construction it is seen that the fuel-handling capacity of each worm is increased at its mounted end, which end supplies the fuel which goes to the sides of the firebox, and so delivers more fuel to the sides thereof.

As various embodiments might be made of this invention, and as various changes might be made in the construction herein described, all 30 without departing from the scope of the invention,

tion, it is to be understood that all matter herein set forth or shown in the accompanying drawings is to be interpreted as illustrative and not in a limiting sense.

I claim:

1. A locomotive stoker screw comprising, a tapered fuel handling screw having a flight extending from its larger end to its smaller end and having an auxiliary flight at the larger end only to increase the fuel handling capacity of the 10 screw at the larger end without increasing the fuel handling capacity at the smaller end.

2. A locomotive stoker screw comprising, a tapered fuel handling screw, said screw having a flight tapering from its larger end to its smaller 15 end, and said screw being provided with means at its larger end only for increasing the fuel handling capacity thereof over and above the fuel handling capacity naturally attending the conical shape of the screw and without increasing 20 the fuel handling capacity of the smaller end of the screw.

3. A locomotive stoker screw comprising, a tapered fuel handling screw, said screw being provided with means at its larger end only for increasing the fuel handling capacity thereof over and above the fuel handling capacity naturally attending the conical shape of the screw and without increasing the fuel handling capacity of the smaller end of the screw. 25

30 WILLIAM THOMPSON HANNA.
